UNITED STATES PATENT OFFICE

2,329,237

SEWING MACHINE

Fred Ashworth, Wenham, Mass., assignor to
 United Shoe Machinery Corporation, Borough
 of Flemington, N. J., a corporation of New
 Jersey

Application September 11, 1940, Serial No. 356,361

7 Claims. (Cl. 112—261)

The present invention relates to sewing machines, more particularly shoe sewing machines wherein many of the operating mechanisms therefor are located in the head portion of the machine, and has as its object the provision of a protective and ornamental enclosure or casing for such mechanisms of novel and improved construction and manner of mounting on the machine.

While some form of casing or enclosure for the head portion of shoe sewing machines has come to be considered desirable to prevent injury to the operator through accidental contact with the operating mechanisms and to prevent the escape of lubricant thrown off from the moving parts, certain difficulties have heretofore stood in the way of providing a satisfactory enclosure. For example, a suitable casing must leave the sewing point of the machine unobstructed to permit ready manipulation of the work. It is likewise essential that the enclosure be quickly and easily removable to afford access to the operating mechanisms, and yet the cover or covers forming the enclosure must be arranged to be firmly secured to the machine to avoid any possibility of loosening, with consequent vibration and noise. Furthermore, since one object in employing a casing or enclosure is to improve the appearance of the machine, the mounting arrangement must not interfere with a smooth exterior appearance.

Accordingly, the present invention contemplates, as a feature thereof, the provision of an enclosure or casing for the operating mechanisms in the head portion of a shoe sewing machine, the enclosure comprising a cover or covers mounted on the machine through the provision of cover supporting and positioning means adjacent the top of the machine, each cover being entirely supported at two points and secured at a third point by clamping means at the side of the machine. More specifically, the invention contemplates a mounting which involves a cover, or each unit thereof, having two points of connection and support located at the top of the machine, upon which the cover by its own weight becomes firmly seated, while the third point of connection, adjacent the lower portion of the cover, comprises a clamp operative in a direction generally perpendicular to a vertical plane passing through the two points of support for securing the cover to the machine.

In the drawing illustrating the invention in its preferred embodiment, Figure 1 is a view in front elevation of the head portion of a shoe sewing

5 machine with the operating mechanisms enclosed, except for the sewing point, by a casing constructed and arranged in accordance with the invention, and Figure 2 is a view in side elevation of the machine and enclosure shown in Figure 1, a portion of one cover being broken away in each figure to show details of the mounting.

The machine in which the invention is shown as embodied for purposes of illustration is of the type illustrated and described in U. S. Patent No. 1,885,927, issued November 1, 1932, to Bernard T. Leveque, and is a McKay type machine having a work supporting horn 6. The stitch forming and work feeding devices are located, together with their operating mechanisms, in the head portion 8, carried by a support or pedestal 10. The various devices are similar in arrangement and operation to those of the aforesaid patent, the devices illustrated comprising a straight hook needle 12, presser foot 14, feed point 16, and shuttle 18. To raise the presser foot manually, a hand lever 20 is provided at one side of the machine head.

To protect and conceal the numerous operating mechanisms in the head of the machine of the patent, an enclosure is provided which substantially encases the head of the machine with the exception of the devices adjacent the sewing point. For convenience in handling, the enclosure is divided along a median line from front to back of the machine into two shell-like parts or covers 22 and 24. The particular shape of these covers, insofar as ornamental appearance is concerned, is disclosed and claimed in Design Patent No. 114,410, issued April 18, 1939 to Frederick A. Prahl, Jr.

In order that these covers may be removed from the machine and replaced with a minimum of time and effort and yet arranged to be firmly secured when in place on the machine, each cover is independently mounted on the head of the machine and is connected thereto at three points only. At two of these points, the cover is merely supported and positioned, the cover resting under its own weight solely upon the hereinafter described supporting devices. At the third point of connection, the cover is clamped, the clamping force being however laterally directed so as in no way to interfere with the proper seating of the cover on the aforesaid supporting devices.

These supporting devices are in the form of headed members or pins having round shank portions 26 secured in vertical bores 28 in the top of the machine frame by means of set screws 30. The head portions 32 of the members are

conical in shape and are arranged to fit within correspondingly tapered sockets or recesses 34 formed in thickened portions 36 on the inside of each cover at the front and back thereof close to the edge constituting the dividing line between the covers.

Vertical adjustment of the position of each cover relative to the machine is effected by raising or lowering the supporting pins in their bores 28 in the machine frame. To make possible lateral adjustment of the covers as well, the supporting pins are constructed with their conical head portions 32 eccentrically disposed or offset with respect to the shank portions 26. By rotating one of the members in the frame, the spacing between two heads may be adjusted to align the latter accurately with the respective cover sockets and thus insure full length seating of the same on the heads, while rotation of both members together provides for bodily displacement of the cover laterally so as to adjust the clearance between adjacent edges of the covers as well as between cover and frame.

To secure the covers against lateral swinging movement after the seating of the sockets 34 on the conical heads 32, a third point of connection of each cover with the machine is provided at the lower edge of the cover. As shown in Figure 2, the covers are formed with a rearward extension or lug 38 slotted at 40 to permit the lug to fit over a threaded stud 42 extending outwardly from the upper portion of each side plate 44 secured to the pedestal 10 and forming part of the ornamental and protective enclosure for the machine. The studs are provided with thumb nuts 48 which may be tightened against the lug to clamp the latter firmly against the side plate 44, a washer 50 being employed to space the cover from the plate and provide a point of connection of relatively limited contact area so as not to twist or warp the cover.

The covers which make up the head enclosure may have such openings as are necessary for the passage of control levers or the like. Thus, in the illustrative embodiment, the cover 24 has a slot 52 through which extends the hand lever 20 by which the presser foot may be raised manually.

In mounting the covers on the machine for the first time, the supporting pins are adjusted both as to height and orientation so that when the cover is in place and the heads 32 properly aligned with and seated in the sockets 34, the inner face of the lug 38 rests against the washer 50 with the sides of the slot 40 out of contact with the stud 42. As a result, the entire support of the cover is derived from the cone-headed members at the top of the machine, the weight of the cover continually urging the parts into wedging contact and hence preventing the development of any looseness or vibration. Upon tightening the thumb nut, the cover is therefore as firmly secured to the machine as if positive clamping means were employed at all connecting points. Nevertheless, removal of the cover merely involves loosening the thumb screw one or two turns, whereupon the cover may be lifted upwardly until the lug 38 clears the stud 42 and the sockets 34 are free of the conical heads 32. Replacement involves no more than the reversal of these steps, the cover being readily positioned by reason of the cone-shaped heads and tapering sockets. A turn or two of the thumb nut then completes the operation.

While the invention has been illustrated as

embodied in a particular type of shoe sewing machine and a particular shape and arrangement of head enclosure therefor, the invention is not so limited, but may be embodied in other machines and enclosures within the scope of the appended claims.

Having thus described the invention, what is claimed is:

1. The combination with a shoe sewing machine having operating mechanisms in the head portion thereof, of an enclosure for said mechanisms, said enclosure being divided along a median line from front to back of the machine to provide a two-part cover, each part of which is independently mounted on the machine at two supporting points adjacent said median line and secured by clamping means at a third point, the cover parts being independently removable from the machine by bodily lifting from said supporting points upon loosening said clamping means.

2. The combination with a shoe sewing machine having operating mechanisms in the head portion thereof, of an enclosure for said mechanisms including a cover, said cover being supported at two points adjacent the top of the machine, and clamping means for securing the cover to the machine, said clamping means operating in a direction generally perpendicular to a vertical plane through the two supporting points.

3. The combination with a shoe sewing machine having operating mechanisms in the head portion thereof, of an enclosure for said mechanisms including a cover, means for supporting said cover, comprising pins mounted in the upper part of the machine head and adapted to engage the underside of the cover, and means for securing the cover, comprising clamping means arranged to engage the cover at a point remote from said supporting pins.

4. The combination with a shoe sewing machine having operating mechanisms in the head portion thereof, of a cover for said mechanisms, means for supporting the cover on the machine, comprising upwardly directed tapering pins, sockets in the cover adjacent the top thereof adapted to receive the pins, and means for securing the cover to the machine, comprising laterally operative clamping means arranged to engage the cover adjacent the bottom thereof.

5. The combination with a shoe sewing machine having operating mechanisms in the head portion thereof, of a cover for said mechanisms, means for supporting the cover on the machine, comprising upwardly extending pins rotatably and vertically adjustable in the machine head adjacent the top thereof, said pins having conical head portions eccentrically disposed with respect to the shank portions of the pins to enable lateral adjustment of the head portions upon rotation of the pins, tapering sockets in the under side of the cover adapted to receive said conical head portions, and means independent of said supporting means for clamping the cover to the machine.

6. The combination with a shoe sewing machine having operating mechanisms in the head portion thereof, of an enclosure including a cover for said mechanisms, devices on the machine head and on the cover cooperating, when brought into engagement, to locate the cover in predetermined position with relation to the head and support the entire weight of the cover in this position while permitting the cover to be lifted bodily to separate it from the machine head.

and additional means below the supporting devices for clamping the cover in said predetermined position.

7. The combination with a shoe sewing machine having operating mechanisms in the head portion thereof, of an enclosure including a cover for said mechanisms, devices at two spaced points on the machine head adjacent the top of the

machine, devices on the cover cooperating with said devices on the machine head to locate the cover in predetermined position with relation to the head and support the cover in this position, and clamping means at a third point below the top for securing the cover in said predetermined position.

FRED ASHWORTH.
